(57) **CLAIM**

The ornamental design for a tire tread, as shown and described.

DESCRIPTION

FIG. 1 is a perspective view of the tire tread of the present application;

FIG. 2 is an enlarged side view thereof; and

FIG. 3 is a front view thereof; and,

FIG. 4 is an enlarged, partial front thereof.

The other side of the tire is identical to FIG. 2. The broken line showings of the sidewall, inner bead, and the peripheral boundary between the tire tread and the sidewall, are included for the purpose of illustrating environment and form no part of the claim.
